UNITED STATES PATENT OFFICE.

ISIDOR KITSEE, OF PHILADELPHIA, PENNSYLVANIA.

CELLULOID.

SPECIFICATION forming part of Letters Patent No. 767,646, dated August 16, 1904.

Application filed May 19, 1899. Serial No. 717,529. (No specimens.)

To all whom it may concern:

Be it known that I, ISIDOR KITSEE, of the city and county of Philadelphia, State of Pennsylvania, have invented certain new and useful 5 Improvements in Celluloid, of which the following is a specification.

My invention relates to an improvement in celluloid.

The object of my invention is to make raw 10 celluloid plastic in a manner more economical than heretofore practiced.

As is well known, raw celluloid can only be used for practical purposes if dissolved or made plastic. To accomplish this, the raw 15 material is dissolved in any of the known solvents—such, for instance, as acetone, ether, and alcohol, &c. This process involves a great waste of material; and it is the object of my invention to prevent such waste.

20 Referring to the drawing which illustrates in diagram my invention, A is a tank or receptacle closed at the top with a lid a'. This tank is provided with the baskets a a, containing the celluloid a² a².

25 B is a retort provided with the tube b, entering the tank A and terminating in the spraying device b'. The retort is held in position by the adjustable ring c of the bracket C and contains the solvent b'. The adjustable 30 burner c' is also attached to the bracket and can be connected, through the pipe c², with a gas-pipe or other suitable source of fuel.

To the upper part of the tank A is connected the worm d, provided with the condensing- 35 reservoir D, placed in the receptacle D' and preferably surrounded with ice. The worm d is provided with the check-valve d'.

The *modus operandi* is as follows: The retort B is filled with the solvent b' and connected to the tube or pipe b at the same time the receptacles a a are filled with the raw celluloid and the worm d connected with the tank, which is then hermetically closed with the lid a'. The fluid in the retort is then 45 heated with the aid of the burner, and as the volatile fluid is evaporated the vapors will

enter the tank A and will attack the raw celluloid contained in the baskets a a, softening the same and making the particles plastic and adhesive. The check-valve d' is attached to 50 the worm d for the purpose that the vapors shall remain in the tank and penetrate the loose celluloid till a prearranged pressure is attained. The surplus vapor will then enter through the worm the receptacle D and be 55 condensed therein again into a liquid state.

I have illustrated the process as being carried out in a comparative small scale with the aid of retorts and adjustable rings; but other devices may be employed for carrying out my 60 invention.

The baskets or receptacles for the celluloid are preferably made, as shown in the drawing, of wire-gauze.

Having now described my invention, what 65 I claim as new, and desire to secure by Letters Patent, is—

1. The process of reclaiming waste pieces or scraps of celluloid, which consists in subjecting said pieces to the action of fumes or vapors of a solvent in a closed receptacle until 70 the solvent has permeated the mass and rendered the same sufficiently plastic for working.

2. The process of reclaiming waste pieces or scraps of celluloid, which consists in subjecting said pieces in a confined space to the fumes or vapors of a material capable of acting as a solvent, allowing said fumes or vapors to accumulate until the solvent has permeated the mass and rendered the same sufficiently plastic 75 for working, and then drawing off said fumes or vapors.

3. The process of reclaiming waste pieces or scraps of celluloid, which consists in placing the pieces in a closed receptacle, subjecting the 85 pieces therein to the fumes or vapors of a material capable of acting as a solvent until the solvent has permeated the mass and rendered the same sufficiently plastic for working, and then drawing off said fumes or vapors. 90

4. The process of reclaiming waste pieces or scraps of celluloid, which consists in placing

the pieces in a closed receptacle, subjecting the pieces therein to the fumes or vapors of a material capable of acting as a solvent until the solvent has permeated the mass and rendered 5 the same sufficiently plastic for working, then drawing off said fumes or vapors, and finally condensing said fumes or vapors.

In testimony whereof I sign my name, in the presence of two subscribing witnesses, this 22d day of April, A. D. 1899.

ISIDOR KITSEE.
